UNITED STATES PATENT OFFICE.

SWITS CONDÉ, OF OSWEGO, NEW YORK.

DESIGN FOR A KNIT SHIRT AND DRAWERS.

SPECIFICATION forming part of Design No. 12,219, dated April 12, 1881.

Application filed December 9, 1880. Term of patent 7 years.

To all whom it may concern:

Be it known that I, SWITS CONDÉ, of Oswego, in the county of Oswego and State of New York, have invented and produced a new and original Design for Knit Shirts and Drawers, of which the following is a specification, reference being had to the accompanying drawings, forming part thereof.

Figure 1, Sheets 1 and 2, represent respectively a knit shirt and knit drawers worked in my design; and Figs. 2 are enlarged views of a piece of knitted fabric, illustrating more fully the configuration of my design.

a a are waving or serpentine stripes, of one or more colors, worked across a differently colored or white body, *b*, said stripes being arranged horizontally in relation to the garment, as illustrated in Fig. 1, Sheets 1 and 2, of the drawings, and in such relation to each other that each stripe *a* shall alternately approach

and recede from its respective adjacent stripes *a a*, as best seen in Fig. 2 of the drawings.

What I claim is—

The design for knit shirts and drawers, consisting of the waving or serpentine stripes *a a*, arranged horizontally in relation to the garment and in such relation to each other that each of said stripes alternately approaches and recedes from its respective adjacent stripes, substantially as described and shown.

In testimony whereof I have hereunto signed my name and affixed my seal, in the presence of two attesting witnesses, at Oswego, in the county of Oswego, in the State of New York, this 27th day of November, 1880.
